UNITED STATES PATENT OFFICE.

CHARLES A. BUSH, OF OSHKOSH, WISCONSIN, ASSIGNOR TO OSHKOSH MANUFACTURING COMPANY, OF OSHKOSH, WISCONSIN, A CORPORATION OF WISCONSIN.

MIXING-MACHINE.

1,268,093.

Specification of Letters Patent. Patented June 4, 1918.

Application filed February 6, 1915, Serial No. 6,463. Renewed April 8, 1918. Serial No. 227,380.

To all whom it may concern:

Be it known that I, CHARLES A. BUSH, a citizen of the United States, and resident of Oshkosh, county of Winnebago, and State 5 of Wisconsin, have invented new and useful Improvements in Mixing-Machines; of which the following is a description, reference being had to the accompanying drawings, which are a part of this specification.

10 The invention relates to mixing machines.

The primary object of the invention is to provide, in mixing and analogous machines, an improved form of slop guard in connection or combination with a pivoted charging 15 and discharging chute, the parts being of such construction as to effectually prevent the mixed material from getting into the socket bearings of the pivot pin for the chute and thereby preventing grinding and 20 undue wearing of the pin and its bearing sockets.

A further object is to provide a device of the character set forth having the above characteristics and at the same time being 25 of such construction that the parts can be most readily and easily assembled and disassembled.

In the drawings Figure 1 is an end elevation of a mixing machine equipped with the 30 improvements embodying the invention; Fig. 2 is an end fragmentary view of the interior of the mixer showing the chute in discharging position; Fig. 3 is a sectional view of one end of the mixer, the chute being 35 shown in discharging position in full lines and in charging position in dotted lines.

The improvements may be attached to the usual form of mixer comprising a mixing drum 4 mounted upon a portable frame 5 40 and having an end opening 6 therein.

A slop guard comprising two plates 7 almost closes the opening 6 and extends below the lower edge of said openings. The inner edges of the plates from a medial portion of the edges upwardly are recessed, as indicated by the numerals 8—8, to form a space to accommodate a chute 9. The plates are also provided with flanges 10—10 which fit within the opening 6, and are in close 45 proximity to the bordering edge of said

opening. The inner meeting edges of the plates below the recessed portions thereof are provided with inwardly-projecting clamping flanges 11—11 extending longitudinally of the edges and provided with 55 openings 12 for the reception of bolts 13, whereby the plates are secured together. The plates are furthermore provided with fastening lugs 14 projecting outwardly through the opening of the chamber and 60 fastened to uprights 15 of the frame 5 of the machine to secure the guard in position within the opening of the mixing chamber. The inwardly-projecting clamping flanges 11 have extending laterally from the upper 65 ends thereof horizontally-extending concave bearing members 16, the curvatures thereof forming longitudinal recesses 17. Sockets 18, which are alined with each other horizontally, are also formed on the plate 70 7, and the outer ends of these sockets are closed, as clearly shown in the drawings. The sockets are designed to receive and hold the opposite ends of a pivot pin 19.

The discharge chute 9 comprises a bottom 75 20, sides 21, the sides of the discharge end of said chute having upwardly extending portions 22 thereon to permit of an efficient removal of the material from the mixer. A plate 23 is secured to the bottom of said 80 chute and has a longitudinally extending bearing portion 24 at one end thereof and a plurality of bearing portions 25 adjacent said bearing 24 and oppositely curved with respect thereto. These bearings 24 and 25 85 are adapted to receive the pin 19 and thereby form a pivotal connection between the chute and the slop guard, the members 16 forming a bearing for the outer sides of the bearings 24 and 25 whereby the bearings 90 24 and 25 will be free to turn upon the pin 19 and within the recesses 17 of the members 16.

The means for operating the chute 9 comprises a lever 26 mounted upon a shaft 27 95 journaled in a bracket 28 mounted upon the frame of the machine and bearings 29 secured to the uprights 15. Disposed between the bearings 29 and secured to the shaft is a sleeve 30 provided with project 100

ing arms 31 forming a yoke and carrying a pin 32 upon which one end of a lever arm 33 is pivotally mounted said arm being pivotally connected at its other end to the bearings 34 on the plate 23 by a pin 35. The swinging of the lever 26 will turn the shaft 27 to swing the yoke arms 31, lever 33 and consequently the chute 7 to move the chute into discharging position.

10 The invention thus exemplifies slop guard which not only serves as such but holds the shafts upon which the discharge chute is pivoted and the guard, fitting as it does tightly against the opening 6 in the drum, 15 no slopping will occur.

From the foregoing description of my invention, it will be seen that I provide a slop guard in combination with a pivoted chute, of such arrangement and construction that 20 the pivot pin upon which the chute is adapted to turn has its opposite ends within bearing sockets formed on the inner sides of the two plates forming the slop guard, and as the outer ends of these bearing sockets 25 are closed, it is obvious that the drippings which occur, especially while the chamber or drum is revolved, will not clog the bearings or pivot pin, owing to the fact that the drippings of cement cannot enter 30 the bearing sockets. By this arrangement a decided advantage is secured, as thereby wear and grinding on the bearing sockets and pivot pin are prevented.

It will be furthermore seen that in order 35 to provide this form of closed bearing socket for the pivot pin it is important that the slop guard be formed of two plates arranged and connected together as shown in the drawings, and as fully described in 40 the specification. Also, by the provision of the two plates forming the slop guard the work of assembling the parts together and disassembling the same is greatly facilitated.

45 In the assembling of the parts the pivot pin is first inserted through the bearings formed by the curved fingers 24 and 25 at the upper end of the plate 23. One end of the pin is then inserted into the bearing 50 socket 18 of one of the plates of the slop guard, and then the other plate of the slop guard is adjusted edgewise toward the first mentioned plate until the opposite end of the pivot pin is received in the other bearing 55 socket. The two plates are then secured together by passing the bolts 13 through the apertures 12 of the clamping flanges 11. The entire structure is now 60 ready to be lifted up to the opening 6 and when tilted the slop guard and one end of the chute can be readily passed through the opening 6 and properly positioned within said opening. Finally the securing lugs 14 are bolted to the frame members 15.

It is obvious that the disassembling of the 65 parts may be as readily accomplished.

What I claim as my invention is:—

1. In a mixing machine, the combination of a chamber having an opening therein, a slop-guard fitted to the opening and provided with a recess extending downwardly from its upper edge for a desired distance to form a space, and said slop guard also provided on its inner side with bearing sockets alined horizontally with respect to each other, the outer ends of said sockets being closed, and said slop guard also provided with a horizontally-extending curved bearing surface, means for supporting the slop guard within the opening of the chamber, a pivot pin having its opposite ends fitting in the sockets of the slop guard, a chute extending through the space of the slop guard, bearing portions connected to the under side of the chute, said bearing 80 portions being oppositely curved with respect to each other and fitting around the pivot pin and received in and bearing upon the horizontally-extending bearing surfaces, and means for turning the chute on its 85 pivot.

2. In a mixing machine, the combination of a chamber having an opening therein, a slop guard fitting the opening and consisting of two plates, the inner edges of said plates from a medial portion thereof upwardly to the upper ends thereof being recessed to form a space and the inner meeting edges of the plates below the recessed portions thereof being connected together 100 and each plate provided with horizontally-extending concave bearing members, and said plates each provided on its inner side with a socket, the sockets being alined horizontally with respect to each other, and each socket having its outer end closed, means for supporting the slop guard plates within the opening of the chamber, a pivot pin having its opposite end fitting in the sockets of the slop guard plates, a chute extending 105 through the space formed by the recessed portions of the slop guard plates, bearing portions connected to the under side of the chute, said bearing portions being oppositely curved with respect to each other, 110 said oppositely curved bearing portions fitting around the pivot pin, and received in and bearing upon the horizontally extending bearing surfaces, and means for turning the chute upon its pivot.

3. In a mixing machine, the combination of a chamber having an opening therein, a slop guard having means for supporting it to said opening and provided with a central recess, a pair of alined oppositely disposed sockets having closed outer ends, and a horizontally disposed bearing surface extending 125 between said sockets and curved in

cross-section, a pivot pin having its ends supported in said sockets, and a chute positioned in said recess and provided with a bearing portion mounted upon said pin between said sockets in engagement with the bearing surface on the guard.

In testimony whereof, I affix my signature, in presence of two witnesses.

CHARLES A. BUSH.
